UNITED STATES PATENT OFFICE.

JOHN L. HARPER, OF NIAGARA FALLS, NEW YORK.

KILN.

1,253,487.

Specification of Letters Patent. Patented Jan. 15, 1918.

Application filed April 29, 1910, Serial No. 558,474. Renewed December 1, 1917. Serial No. 204,990.

To all whom it may concern:

Be it known that I, JOHN L. HARPER, a citizen of the United States, residing at Niagara Falls, in the county of Niagara and 5 State of New York, have invented certain new and useful Improvements in Kilns, of which the following is a specification.

My invention relates to a method and apparatus for the treatment of materials or 10 articles which in the course of such treatment are subjected to high temperatures. The process is particularly applicable in electrically heated kilns of the kind shown in U. S. Patent No. 925,902, granted June 15 22, 1909, to Harper and Larkworthy.

In such kilns, in which the heat is generated by the passage of an electrical current through resistors, it has been found that temperatures of almost any degree may 20 be produced, such temperatures being attainable in combustion furnaces only when the flame is oxidizing in character.

The present invention relates to the maintenance in kilns of this type of any desired 25 atmosphere by the introduction of suitable gases, whether such gases are neutral, reducing, carbonizing, or oxidizing in character, or of such other character as may enable the production of any desired effect on the 30 materials being treated.

Thus in the manufacture of various forms of pottery articles it is of a highest importance that the atmosphere of the muffles or kilns in which the articles are burned shall be of the proper character. In the burning 35 of certain porcelains, where temperatures as high as 2200° F., must be used, it is essential that a reducing atmosphere should be maintained. So also in the firing of articles 40 which have glazes containing metallic coloring ingredients, such as silver or copper compounds, it is necessary to have the atmosphere of the kiln under control, as the color of the finished product depends upon the 45 state of oxidation of the metals in the glaze. In the firing of other classes of pottery articles, in which metallic oxids are used as coloring materials in the glaze, it is important that the atmosphere should not be reducing in character but should be neutral 50 or even oxidizing.

In the heat treatment of metals, such as iron or steel, which are readily oxidizable at high temperatures, such oxidation can 55 readily be obviated by introducing suitable neutral or non-oxidizing gases into the kiln.

Or when iron or steel articles are to be carbonized, as in the manufacture of armor plate, an atmosphere of carbon-containing gases may be maintained.

In the baking of carbon articles it is of course highly important that no oxidizing atmosphere should remain in the kiln.

My invention therefore resides in the treatment of articles in electrically heated 65 kilns in the presence of a suitable atmosphere, such atmosphere being produced by displacing the air which will be normally present in the kiln, by such gases as producer gas, deoxidized air or nitrogen, hydro- 70 carbon gases or other gases by which it is desired to produce some chemical or physical effect upon the material being treated.

This process may be carried out in the kiln such as is shown in the accompanying 75 drawings, in which:

Figure 1 is a longitudinal vertical section of a portion of the kiln;

Fig. 2 is a transverse vertical section on the line C—C of Fig. 1; and

Fig. 3 is a transverse vertical section on lines D—D of Fig. 1.

The furnace shown in the drawings is of the type illustrated in the patent before referred to, and consists of a long tunnel provided with a double track on which trains of cars can be moved in opposite directions, these cars being preferably of the construction illustrated in the patent above referred to. These cars have at each end upwardly 90 extending walls which divide the tunnel into a series of chambers. The general mode of operation of the present device is the same as that described in that patent.

Considering now the chamber in the middle of the tunnel, the gas is introduced from any suitable source of supply through the flue 1 whence it passes to the flue 2, longitudinally arranged within the wall of the furnace, and hence into the transverse flues 100 3, 3 arranged in the roof of the kiln, from which flues the gases pass into the furnace chamber proper. It will be noted that the arrangement of flues is such that the entering gases will be heated by contact with the 105 walls and roof portion of the furnace practically to the temperatures which may exist in the kiln chamber. The gases introduced into the central chamber pass in each direction outwardly into the adjoining chambers 110 and displace the air therein and escape through the flues 5, 5 in the adjoining cham-

bers. The entrance flue 1 and the exit flues 5, 5 are each provided with dampers 10, 11, so that the rapidity of flow of the gases through the furnace can be controlled. An 5 additional gas supply for each chamber may be provided as shown in Fig. 3 by connecting the gas supply with the entrance flue 6 which is connected with the flues 7, 7 and transverse flues 8, 8 in the same manner as 10 heretofore described for the central chamber. R, R are electrical heating resistors.

Only three chambers have been shown as provided with a gas supply, but it is of course obvious that as many of the chambers

15 in the series, usually thirteen, may be similarly connected to the gas supply, and that by a proper arrangement of conduits, the same gas supply may be connected to as many chambers as desired.

20 A suitable apparatus, such as a pump or blower, for forcing the gases into the furnace and exhausting them therefrom may of course be provided if desired.

In operation, the materials to be treated 25 are placed on the cars, and are gradually heated as they progress toward the middle chamber of the furnace where they are subjected to the intense heat radiated from the resistor R. While being so heated they are 30 subjected to the actions of the gases introduced into the kiln chambers in the manner above described.

While I have described the operation particularly in connection with a kiln of the 35 kind shown in the patent above referred to,

I do not of course wish to be limited to this particular type of electrically heated kiln, as manifestly kilns of other construction may be used to carry out my process, as long as the articles are heated by radiation from 40 electrically heated resistors and are maintained in a predetermined atmosphere of the kind described.

It is also apparent that the introduction of gases of a predetermined composition 45 may serve to wash or force out of the furnace any other gases that may be in the furnace, thereby eliminating the detrimental effects of such gases on the wares being treated.

What I claim is:

1. A tunnel kiln having the median portion thereof provided with an electrical heating means, flues for introducing gases into such median portion and means for 55 forcing gas into said flues.

2. A tunnel kiln provided with electrical resistors for heating the same located at its median portion, flues for introducing gas into the furnace at such median portion, and 60 exit flues from the kiln arranged at both sides of such median portion, whereby the kiln may be filled with an atmosphere of gas.

In testimony whereof, I affix my signature in presence of two witnesses.

JOHN L. HARPER.
